[57] CLAIM

The ornamental design for a physiologic monitor or the like, substantially as shown.

DESCRIPTION

FIG. 1 is a top plan view of a physiologic monitor showing our new design;

FIG. 2 is a right-side elevation of the physiologic monitor illustrated in FIG. 1;

FIG. 3 is a bottom plan view of the physiologic monitor illustrated in FIG. 1;

FIG. 4 is a left-side elevation of the physiologic monitor illustrated in FIG. 1;

FIG. 5 is a front elevation of the physiologic monitor illustrated in FIG. 1; and

FIG. 6 is a rear elevation of the physiologic monitor illustrated in FIG. 1.

*FIG. 1**FIG. 2**FIG. 3*

*FIG. 4**FIG. 5**FIG. 6*
